UNITED STATES PATENT OFFICE.

WILLIAM A. DUNCANSON, OF BROCKTON, MASSACHUSETTS.

ANCHOR.

SPECIFICATION forming part of Letters Patent No. 730,009, dated June 2, 1903.

Application filed December 13, 1902. Serial No. 135,040. (No model.)

To all whom it may concern:

Be it known that I, WILLIAM A. DUNCANSON, a citizen of the United States, and a resident of the city of Brockton, in the county of Plymouth and State of Massachusetts, have invented a new and Improved Anchor, of which the following is a full, clear, and exact description.

This invention relates to improvements in ships' anchors; and the object is to provide a yielding connection between the anchor and the anchor chain or cable, thus preventing the breaking of the chain or cable by sudden shocks or pulls due to the motion of a vessel while at anchor.

I will describe an anchor embodying my invention and then point out the novel features in the appended claims.

Reference is to be had to the accompanying drawings, forming a part of this specification, in which similar characters of reference indicate corresponding parts in both of the figures.

Figure 1 is a plan view, partly in section, of an anchor embodying my invention; and Fig. 2 is a longitudinal section through the shank thereof.

Referring to the drawings, 1 designates the shank of the anchor, 2 the arm thereof, and 3 the flukes, having swinging connection with the arm. The shank 1 is tubular, and movable in the shank is a rod 4, on the outer end of which is a ring 5, to which a chain or cable 6 is to be attached. This rod 4 is movable through an opening in a partition 7, secured in the shank at about its center. On the lower end of the rod is a piston 8, and a piston 9 is also connected to the rod above the partition 7. These pistons are perforated for a purpose which will be hereinafter described.

Arranged in the compartment in which the piston 8 operates is a liquid 10, and in the compartment in which the piston 9 operates is a liquid 11. The liquid may be oil or similar material not subject to freezing. Also arranged in the compartments are springs 12 and 13, the spring 12 abutting against the partition 7 and piston 8, while the spring 13 abuts against the piston 9 and the end wall of the shank.

Secured to the shank at the end and at opposite sides are cylinders 14 for containing liquid, and operating in these cylinders are

perforated pistons 15, the stems 16 of which slide through openings in the end closure of the cylinder and connect with a cross-head 17, attached to the rod 4, and springs 18 are arranged between the pistons and the end closure. These auxiliary pistons and springs serve to check the continuous draft on the main pistons and springs—that is, when the auxiliary devices are completely compressed the main devices will not be fully compressed, so that a complete elastic cushion is obtained. By perforating the pistons the bearing thereon will be relieved to some extent, as the liquid will pass through said perforations as the pistons move upward. The four springs act in conjunction in throwing back the pistons upon the slackening up of the chain or cable. The liquid in the chambers is to perform the hydraulic action when pressure is brought to bear.

Having thus described my invention, I claim as new and desire to secure by Letters Patent—

1. An anchor having a tubular shank, a cushioned piston therein, and means for connecting the piston to a chain or cable.

2. An anchor having a tubular shank, a rod movable in said shank, a piston on said rod, and a spring surrounding the rod, the said spring bearing at one end against the piston and at the other end against a fixed part in the shank, substantially as specified.

3. An anchor having a tubular shank, a rod movable in said shank, a perforated piston on said rod, a spring surrounding the rod and engaging at one end with the piston and at the other end with a fixed part in the shank, and a liquid in the shank, substantially as specified.

4. An anchor having a tubular shank, a partition arranged in said shank and having an opening, a rod movable in said shank and through said opening, a perforated piston on the rod below the partition, a perforated piston on the rod above the partition, springs engaging with said piston and with fixed parts of the shank, and a liquid in the shank, substantially as specified.

5. An anchor having a tubular shank, a rod movable in the shank, a piston on said rod, a spring arranged between said piston and a fixed part in the shank, liquid-cylinders on

the end of the shank, and pistons in said cylinders having connection with the rod.

6. An anchor having a tubular shank, a rod movable in the shank, a piston on said rod, a spring between said piston and a fixed part in the shank, cylinders on the end of the shank, pistons operating in said cylinders, stems extended from the pistons to connections with the rod, and springs pressing upon said pistons, substantially as specified.
- 5
7. An anchor having a tubular shank, a cushioned piston in said shank and having
- 10

connection with the anchor chain or cable, and auxiliary cushioned pistons having connection with the chain or cable, substantially as specified.

In testimony whereof I have signed my name to this specification in the presence of two subscribing witnesses.

WILLIAM A. DUNCANSON.
